TABLE

Hester Covington, 229 Woodlawn Ave.,
Jacksonville 4, Fla.

Filed Apr. 19, 1963, Ser. No. 74,523

Term of patent 14 years

(Cl. D33—14)

FIG. 1

FIG. 2

The dominant features of my design reside in those portions shown in full lines on the drawing and consist primarily in the electroluminescent insert in the top thereof.

I claim:

The ornamental design for a table, as shown and described.
